UNITED STATES PATENT OFFICE.

GEORGE S. KENT, OF LYNDON, VERMONT.

FURNACE.

SPECIFICATION forming part of Letters Patent No. 771,159, dated September 27, 1904.

Application filed October 7, 1903. Serial No. 176,074. (No model.)

To all whom it may concern:

Be it known that I, GEORGE S. KENT, a citizen of the United States, and a resident of Lyndon, in the county of Caledonia and State of 5 Vermont, have invented a new and Improved Furnace, of which the following is a full, clear, and exact description.

The purpose of the invention is to provide a furnace of simple, durable, and economic construction capable of utilizing all the products of combustion to a maximum extent, in which furnace a continuous combustion-chamber is provided and two fuel-chambers in communication with the combustion-chamber, together 15 with means for admitting air and steam to the combustion-chamber and for the admission of stoking-tools to the fuel-chambers.

A further purpose of the invention is to provide convenient means for operating the grate-bars from the exterior of the furnace.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a transverse section through the 30 furnace, taken practically on the line 1 1 of Fig. 3. Fig. 2 is a front elevation of the furnace. Fig. 3 is a longitudinal vertical section through the furnace, taken substantially on the line 3 3 of Fig. 1; and Figs. 4 and 5 are 35 detail sectional views illustrating slight modifications in the formation of the combustion-chamber for the furnace.

The front wall 10, the back wall 11, and the side walls 13 of the furnace are preferably 40 made of brick, although any other suitable material may be employed, and these walls are provided, preferably, with an outer jacket 14, of metal. At the central portion of the furnace a partition 15 is constructed of fire-proof material, and this partition is preferably of pyramidal form, as is illustrated in Figs. 1, 4, and 5. The top portion of the furnace may be constructed in different ways, but is provided under all conditions with 45 metal side sections 16, having marginal flanges 50

17 extending down over the upper portions of the outer jacket 14, and in these upper side sections 16 openings 18 are produced, normally closed by covers 19, as is illustrated in Fig. 1. In said Fig. 1 in addition to the 55 side sections 16 the top of the furnace consists of a segmental dome-section A, properly supported by the said side sections 16, and this dome-section A may be either permanent or it may be removable, as desired. 60 Bars 20 extend from the top of the central partition 15 in opposite directions to the side portions of the dome A. These bars are therefore in opposing series, and the bars of a series are spaced one from the other a suitable distance, thereby providing what I term a "combustion-chamber" B, having an outlet 21 at the rear of the furnace, adapted to be connected wherever desired. In Fig. 4 the combustion-chamber B is shown of different 65 form, as the central portion A' of the top is flat or continuous in the same horizontal plane with the side top sections 16, and in Fig. 5 I have illustrated another slight deviation in the construction of the combustion-chamber B, 70 wherein instead of a segmental dome A being provided for the top of said chamber the top A' is of angular or V shape. Otherwise the construction of the top of the furnace is the same as that shown in Fig. 1. 75

The grate-bars C are in two series, located at each side of the central partition 15, as is shown in Figs. 1 and 3. These grate-bars C of a series are connected at the top by a longitudinal bar 21^a and near their bottom ends 80 by a longitudinal bar 22. The bottom ends of the grate-bars are adapted to rest against the inclined surfaces of the central partition 15 when the grate-bars are in closed position, as is shown in Fig. 1, and the upper connecting-bars 21^a of the grate-bars have hinged connection 23 with suitable supports 24, located at the upper side portions of the interior of the said furnace, as is also shown best in Fig. 1. Sectors 25 are shown in Fig. 1 as 95 hinged at 27° to the lower connecting-bars 22 of the grate-bars C, and, as is illustrated in Fig. 3, these sectors are preferably three in number for each series of grate-bars, one sector being located about centrally between the 100

ends of the series of grate-bars and the other two at or near the ends of the series. These sectors 25 are provided with top and bottom teeth 26, adapted to engage with upper and lower 5 pinions 27 and 28, secured upon upper and lower shafts 29 and 30, mounted to turn in the side walls 13 of the furnace, and where the sectors 25 are located suitable openings 31 are produced in the side walls. Said openings are 10 normally closed by doors 32 of any approved construction, which doors are opened when the grates are to be dumped to enable the sectors 25 to pass outwardly at their outer ends beyond the outer faces of the side walls of the 15 furnace. One of the shafts, preferably the upper shaft 29, is provided with a hand-wheel 33 at the front end of the furnace, as is shown in Fig. 2, whereby to operate the pinions 27 and 28, and in order that the grate-bars may 20 be held positively in open or in closed position ratchet-wheels 39 are secured on one of the shafts carrying the sprocket-wheels 27 and 28, which ratchet-wheels are engaged by suitable pawls 40, as is clearly shown in Fig. 2. Thus 25 it will be observed that when the grate-bars are in the closed position (shown in Fig. 1) two fuel-chambers D are formed, and these fuel-chambers D have communication with the combustion-chamber B through the spaces 30 between the bars 20, forming the sides of the said combustion-chamber.

More or less air can be admitted to the combustion-chamber B by opening doors 34 at the front of the furnace, mounted to slide in suitable guides 35, and attention may be given to the fire in the fuel-chambers D by the use of suitable stoking-tools. At the front of the furnace doors 36 are located, adapted to uncover openings leading to the fuel-chambers 40 D, and the said doors are ordinarily mounted to slide in suitable ways 37, while access is obtained to the two ash-pits through doors 38, also located at the front of the furnace.

In order to facilitate combustion, a steam- 45 pipe 41 is made to pass through an opening 42 in the front of the furnace; but the nozzle end of the said steam-pipe does not extend into the interior of the furnace, so that when the steam enters the combustion-chamber it 50 will have been thoroughly mixed with the admitted air.

In order that the two shafts 29 and 30 shall move together when the hand-wheel 33 is revolved, gears 43 and 44 are preferably located at the rear ends of the shafts, which gears are in mesh one with the other at each 55 series of shafts, as is shown in Fig. 3.

Having thus described my invention, I claim as new and desire to secure by Letters Patent— 60 1. In a furnace a combustion-chamber, fuel-chambers in communication with the combustion-chamber, pivoted grate-bars, toothed sectors hinged to the free ends of said bars, shafts extending longitudinally in the sides of the 65 furnace, and projecting at the front end there-

of, pinions carried by said shafts and engaging said sectors, and means on the projecting ends of said shafts for rotating the same to operate the grate-bars.

2. In a furnace, a central partition, a combustion-chamber supported by the said partition, a fuel-chamber at each side of the combustion-chamber, being in communication with the combustion-chamber, grate-bars for the fuel-chambers, pivoted at their upper ends 75 and normally held with their lower ends in engagement with the sides of said partition, and means extending without the furnace for manually carrying the grate-bars from a closed to an open position and back to a closed position, as described. 80

3. A furnace provided with a central partition cone-shaped in cross-section, a combustion-chamber supported by the said partition, having fenestrated sides and an outlet, grate-bars hinged at each side of the combustion-chamber, having a downward inclination from the upper portion of the furnace into engagement with the said conical partition, forming fuel-chambers in communication with the combustion-chamber, bars hinged at their inner ends to the lower ends of said grate-bars, and means operatively engaging said bars to swing the grate-bars on their pivots. 90

4. A furnace provided with a central partition, a combustion-chamber supported by the said partition, having fenestrated sides and an outlet, grate-bars hinged at each side of the combustion-chamber, having a downward inclination from the upper portion of the furnace to the said partition, forming fuel-chambers in communication with the combustion-chamber, means for operating the grate-bars, toothed sectors hinged to the lower portions 100 of the grate-bars, shafts journaled in the sides 105 of the furnace, pinions carried by the said shafts, between which the sectors have movement, and means for operating the said shafts from the exterior of the furnace, as set forth. 110

5. In a furnace, a central partition, having 110 its side walls converging upwardly, a combustion-chamber above said partition and having fenestrated sides, a fuel-chamber at each side of the combustion-chamber and in communication therewith, said fenestrated sides 115 of the combustion-chamber forming the inner walls of the fuel-chamber, grate-bars forming the outer walls of the fuel-chamber, said bars being held with their lower ends adapted to swing into engagement with the inclined sides 120 of the partition of the furnace, and means connected with the lower ends of said grate-bars for manually controlling the same. 125

In testimony whereof I have signed my name to this specification in the presence of two subscribing witnesses.

GEORGE S. KENT.
